ABSTRACT: A valve trumpet is provided with a tapered lead pipe directly connected with the inlet of a valve assembly, a bell and a telescopic connector disposed at the end of the bell to connect the inlet of the bell with the outlet of the valve assembly. Said bell connector has an outer tube and an inner tube slidable through the outer tube so as to tune the trumpet to a desired pitch.

VALVE TRUMPET

This invention relates to brass-wind musical instruments and more particularly to valve trumpets.

The prior valve trumpets whether of the piston valve type or rotary valve type comprised a bell, a valve assembly and a lead pipe including as a tuning slide two sets of straight outer tubes each containing an inside tube which was slideable through the outer tube so as to tune the trumpet. Although it was more advisable for the lead pipe to be continuously tapered from the mouthpiece to the inlet of the valve assembly so as to increase the freedom of air passage without strains of sound waves and ease performance in desired harmonics, it was difficult to shape the lead pipe into a continuously tapered form due to the presence of said sets of tuning slides at the intermediate points of the lead pipe. For a similar reason, the lead pipe with the tuning slide resulted in an unstable tonal pitch.

It has also been known that the valve trumpet had a bell separable into two members at an intermediate point so as to permit the forward member (flare portion) of the bell to be replaced with another which would bring about a different musical key and tone colour. However, it has been found that in actual performance, a mere replacement of said forward member did not exhibit the aforesaid desired effect.

An object of this invention is to provide a valve trumpet improved so as to increase the freedom of air passage without strains of sound waves, ease performance in desired harmonics and keep a stable tonal pitch.

In an aspect of this invention, the valve trumpet therefore comprises a valve assembly, a tapered lead pipe directly connected with the inlet of the valve assembly, a bell with a crooked portion, and a telescopic connector disposed at the end of the bell to connect the inlet of the bell with the outlet of the valve assembly, said bell connector having an outer tube and an inner tube slideable through the outer tube in an air tight manner so as to tune the trumpet in a desired pitch.

Another object of this invention is to provide a valve trumpet including a bell with a crooked portion detachable from the outlet of the valve assembly so as to permit the bell to be replaced with another which will bring about such variations in the musical key and tone colour as will produce satisfactory effects in actual performance.

A further object of this invention is to provide a valve trumpet including means for holding the bell in a manner to slidably guide the bell in parallel to the axis of the connector so that the connector is slidably extended and pulled back without any inconvenient effects such as bending and deformation.

The present invention can be more fully understood from the following detailed description when taken in connection with the accompanying drawings, in which:

FIG. 1 is a side elevational view of a valve trumpet embodying this invention;

FIG. 2 is a plane view of the valve trumpet shown in FIG. 1;

FIG. 3 is a rear end view of the valve trumpet; and

FIG. 4 is a perspective view of the valve trumpet.

Referring to the drawings, the valve trumpet of this invention includes a lead pipe 1, a valve assembly 2 and a bell 3 with a crooked portion 3a. The lead pipe 1 is continuously tapered from one end, to which a mouthpiece 4 is detachably connected, to the other end connected with the inlet 5 of the valve assembly 2, and directly connected with the valve inlet 5 without the necessity of interposing two sets of telescopic connectors for tuning the trumpet as was required in the prior art.

The valve assembly 2 is provided with three valves 2a, 2b and 2c each having a cylindrical casing 6, a piston including a rod 7, and a finger button 8 disposed at the top of the piston rod 7. The bell 3 communicates with the outlet 9 of the valve assembly 2 through a telescopic connector 10 engaged with the inlet of the bell 3. Namely, the telescopic connector 10 includes an outer tube 10a which is formed into a cylinder having a uniform diameter and the fore end of which is immovably fixed to the rear end of the bell and an inner tube 10b which is slidably inserted into the outer tube 10a in an air tight

manner and the rear end of which is immovably fixed to the tubular portion of the valve outlet 9. The inside wall of the slide tube 10b is tapered continuously towards the inside wall of the bell 3, in a manner to form a substantial continuation of the inner end of the bell. Therefore, air can flow freely through the connector 10 without any substantial turbulence with the resultant prevention of sound waves from suffering any strains. Or instead, the inlet portion of the bell 3 as well as the inside wall of the slide tube 10b may be cylindrical without taper.

Since the aforementioned trumpet includes a single telescopic connector 10 disposed at the outlet of the valve assembly, it is possible to increase the freedom of air passage without strains of sound waves and ease performance in desired harmonics. The tapered lead pipe 1 without any slides results in a stable tonal pitch together with the aforesaid satisfactory effects.

The valve inlet 5 includes a tubular portion mounted on the casing of the third valve 2c and the tubular portion of the valve outlet is disposed on the casing of the first valve 2a. Each of the three valve casings communicates with a crooked tube 11 as well known.

On the side of the valve casings is disposed means for holding the bell 3 thereto. Said holding means includes a guide rail 12 mounted on the valve casings by means of brazing in parallel to the axis of the bell connector 10, as well as a movable frame 13 which is rigidly secured to the forward section of the bell 3 disposed beyond the crooked portion 3a and is also slidably fitted to the rail 12 so as to be guided in parallel to the connector axis thereby to slide the inner tube 10b through the outer tube 10a for tuning the trumpet. The guide rail 12 is bridged between the first and third casings. The frame 13 has the same length as the guide rail so as sufficiently to support the bell only by the holding means. Since the bell is guided exactly along the rail 12, the connector 10 is slidably extended and pulled back without any inconvenient effects such as bending and deformation. The frame 13 is provided with a set screw 14 to be fixed to the rail 12.

In this embodiment, the frame 13 may have a cross section of a dovetail groove form. The set screw 14 is preferably disposed at a level at which it never obstructs the operation of the finger buttons. The set screw is further preferably positioned at the fore end of the rail 12 and between the second and third casings when the trumpet is tuned to the Standard Pitch of $A_4=440\text{ Hz.}$ by the sliding adjustment of the outer tube 10a relative to the inner tube 10b.

Furthermore, the outer tube 10a may be detachable from the inner slide tube 10b so as to permit the bell to be replaced with another which will bring about such variations in the musical key and tone colour as will produce satisfactory effects in actual performance. Since the bell is supported at a single point, the transmission of the bell vibration will be scarcely obstructed. In this embodiment, the connector 10 is composed of the inner tube and the outer tube arranged in the order mentioned in the direction of air flow so as satisfactorily to prevent the air through the connector from being leaked, and disposed at the beginning of the bell, a position where the tube is least or not tapered so as to reduce the strains of sound waves as much as possible.

While the invention has been described in connection with some preferred embodiments thereof, the invention is not limited thereto and includes any modifications and alterations which fall within the scope of the invention as defined in the appended claims.

I claim:

1. A valve trumpet comprising:
a valve assembly 2, with an inlet and outlet 9;
a lead pipe 1 connected with the inlet of the valve assembly
and tapered continuously from one end thereof to the
other;
a bell 3 with a crooked portion 3a;
guide means 12 for holding and slidably guiding said bell;
and

a telescopic connector 10 disposed at the end of the bell to connect the inlet of the bell with the outlet of the valve assembly, said connector having an outer tube 10a and an inner tube 10b slidable through the outer tube in an air tight manner, said outer tube being immovably fixed to the end of the bell and the inner tube being immovably fixed to the tubular portion of the valve assembly outlet.

2. A valve trumpet claimed in claim 1 in which the outer tube is detachable from the inner slide tube so as to permit the bell to be replaced with another.

3. A valve trumpet claimed in claim 1 in which said guide means includes a guide rail mounted on valve casings and a frame secured to the forward section of the bell disposed beyond the crooked portion, said frame being movable relative to the guide rail.

4. A valve trumpet claimed in claim 3, in which a set screw is provided on the frame so as to fix the frame to the guide rail.

5. A valve trumpet claimed in claim 4, in which the set screw is positioned between the second and third casings of the valve assembly when the trumpet is tuned to a standard pitch by the sliding adjustment of the outer tube relative to the inner tube.

6. A valve trumpet claimed in claim 1, in which the inner wall of the inner tube is tapered continuously toward the inner wall of the bell in a manner to form a substantial continuation of the inner end of the bell.

10 7. A valve trumpet claimed in claim 1, in which the inner wall of the inner slide tube, as well as inner wall of the bell at its inlet portion is not tapered.
